BATHTUB

Clarence J. Rodman, Alliance, Ohio

Application June 7, 1948, Serial No. 146,793

Term of patent 14 years

(Cl. D4—4)

To all whom it may concern:

Be it known that I, Clarence J. Rodman, a citizen of the United States, residing at Alliance, in the county of Stark and State of Ohio, have invented a new, original, and ornamental Design for a Bathtub, of which the following is a specification, reference being had to the accompanying drawing, forming part thereof.

Fig. 1 is a view in perspective of the bathtub;
Fig. 2 is a section on the line 2—2 of Fig. 1; and
Fig. 3 is a section on the line 3—3 of Fig. 1, showing my new design.

The dominant features of the invention lie in the matter shown in full lines in the drawing.

I claim:

The ornamental design for a bathtub, as shown and described.

CLARENCE J. RODMAN.
